TELESCOPIC PISTON TYPE LIFTING JACK

William E. Pitts, Bloomington, Ind.

Application April 8, 1949, Serial No. 86,230

5 Claims. (Cl. 121—46)

1

This invention relates to improvements in lifting jacks and more particularly to lifting jacks designed as permanently positioned units for the axles of motor vehicles and the like. For the purposes of illustration in the present specification, the use of the device for the changing of tires is hereinafter described, but it is to be understood that the invention is not limited to this particular field of service.

One object of the invention is to provide a 10 permanently positioned unit carried by the axle assemblage in normally inactive or collapsed status but which is available for active service to raise the axle to the desired extent to permit removal and replacement of a wheel. The jack assembly may be a single unit for the axle, thus raising the entire axle, or the axle may have individual units for each wheel.

Another object of the invention is to provide a device formed of sections and capable of movement between nested and expanded positions, the nested position being that in which the structure is being carried in its inactive position on the vehicle, thus permitting the vehicle to travel with a reasonable road clearance, and, at the same time, when expanded, to meet any reasonable lifting requirement with respect to the axle, the sections being arranged telescopically and so formed as to be expanded by controlled fluid pressure.

To these and other ends, therefore, the nature of which will be more clearly explained as the invention is hereinafter disclosed, said invention consists in the improved constructions and combinations of parts hereinafter described, illustrated in the accompanying drawings, and more particularly pointed out in the appended claims.

In the accompanying drawings, similar reference characters indicate similar parts in each of the views, and

Figure 1 is a side elevation of one of the lifting jacks shown in its inactive position;

Figure 2 is a vertical sectional view of the same with the structure partially expanded;

Figure 3 is a sectional view taken on line 3—3 of Figure 2;

Figure 4 is a view, partly in section and partly in elevation, with the parts in their inactive position;

Figure 5 is a view similar to Figure 2 with certain of the parts in a different position; and

Figure 6 is a view partly in elevation and partly in section, showing the assembly in its fully expanded position.

In the present invention, designed particularly for operation by air pressure, the disclosure is restricted to the structure of the jack assembly per se, the details relative to the air supply being omitted, since this can be provided in many different ways. For the purpose of the disclosure, the air supply may be assumed to be from a storage supply, although, in practice, the vehicle

2

will carry means for developing the needed air pressures. In other words, the disclosure refers to the structure of the jack assembly rather than to the particular medium through which it is operated. This is for the reason that the structure can be, with minor changes, utilized with oil as the operating medium.

A jack assembly of the present invention must be formed of at least two sections telescopically arranged. In the specific service herein disclosed, at least three sections are essential, due to the fact that the space below the vehicle axle is limited as to height from the traction surface, and the assembly must be capable of being nested into a compass which will leave a reasonable road clearance below. At the same time, the device must be capable of bridging such height as well as of providing additional expansion sufficient to raise the axle the distance required to permit the desired wheel changes.

In the drawings the jack assembly, as an entirety, is indicated at 10, with the sections indicated as 11, 12 and 13, respectively. Of these sections, section 11 is the outer section, 12 the inner section, and 13 the intermediate section. Each section is annular in form and relatively dimensioned as to permit proper nesting as presently described in detail and as indicated in Figure 4.

The section 11 is of a desired vertical length and has a top 11a, the side wall being circular in contour and of desired thickness. Top 11a carries a controllable port 14, for air supply under pressure, and a controllable port 15 for air exhaust purposes. The top also preferably carries one or more bleeding ports 16, normally closed by a screw plug 16a, for permitting more rapid air discharge when rapid nesting of the assembly is desired. At the bottom of the section 11 there is formed externally an annular rib 11b designed to cooperate with latching members to hold the assembly in nested position, as presently described. The lower zone of section 11 is threaded internally. The wall of the threaded zone is of decreased thickness, as at 11c, to receive an annular packing formation 17 formed in two parts with an intervening packing, the upper of such parts carrying an upwardly-extending annular shoulder 17a, the top of which is located above the plane of a controllable side port 18; the port 18 is equipped with a three-way valve or its equivalent to permit its use for supply or exhaust service at will. If desired, additional ports 18a, normally closed by threaded plugs 18b, may be employed, these being positioned below the top plane of shoulder 17a.

The intermediate section 13 is annular and of circular contour and with open top and bottom. Its external diameter is materially less than the internal diameter of section 11, thereby providing an annular space or chamber 19 between the two sections above formation 17 and to which

port 18 is accessible, the inner face of the formation 17 fitting the exterior wall of section 13 to permit sliding movement of the section relative to the formation but to prevent leakage of content from space 19 through the formation 17. The upper zone of the wall of section 13 is reduced in thickness to provide an external thread zone 13a adapted to receive the members of an annular sliding flange 20, the external diameter of which closely fits the interior of section 11. Section 13 is thus supported telescopically relative to section 11 and in axial alignment therewith, such sliding movements being active to vary the dimensions of space 19. However, the downward movement of section 13 is limited by contact of flange 20 with the top of shoulder 17a, leaving port 18 exposed to such space 19 in all positions of the section. The lower zone of section 13 is also of reduced thickness and provided with an internal thread zone 13b adapted to receive an annular packing formation 21, similar in type to formation 17, provided with upwardly extending shoulder 21a. The wall of section 13 is provided with two or more spaced ports 22 positioned below the top plane of shoulder 21a but above the top plane of shoulder 17a when section 13 is in nested position.

Section 12 is the inner section and its body is circular in contour and of materially less external diameter than the internal diameter of section 13, thereby forming a space or annular chamber 23 between the two sections. Section 12 includes a closed top 12a, preferably formed with a depressed zone 12b on its upper face. This top zone is provided with an external thread 12c to receive the members of an annular sliding flange 24 the exterior of which is adapted to have sliding contact with the interior of section 13. Since the exterior of the body of section 12 is also in sliding contact with the inner face of packing formation 21, it will be understood that section 12 is supported telescopically relative to section 13 and in axial alignment therewith, with the sliding movements of section 12 or 13 or of both sections active to vary the dimensions of space or chamber 23.

As indicated clearly in Figure 2, the lower end of section 12 is closed by bottom member 12d threadedly connected to the lower end of the section. Member 12d is formed with a projecting threaded boss 12e designed to carry and support the foot member 25, the latter being circular in contour and dimensioned to overlie rib 11b when the jack is in its nested position as indicated in Figure 4. The periphery of member 25 carries spaced upwardly extending spring hooks 26 adapted to snap over the rib when the parts are in the position shown in Figure 4, thus retaining the assembly inactive. If desired, the lower face of member 25 may be shaped as shown with a central boss 25a designed to normally provide the actual contact with the traction surface when the assembly is in use. In Figures 5 and 6 the boss 25a is shown as supported on a block 30 which forms no part of the invention.

As will be understood from Figure 2, showing section 12 as completely closed, the section is a hollow section serving merely as the movable foot carrier and is subjected to air pressure—during the expansion cycle—only at its top surface; during the nesting cycle the underside of the flange 24 of the section is subjected to air pressure within space 23 to raise the section. As presently described, the air pressure conditions

for sections 11 and 12 are somewhat different from those of section 13.

The assembly is mounted on the vehicle in any convenient manner, the drawings showing a bracket 35 secured to the exterior of section 11, this being secured to the under side of a vehicle part 36 which may be part of an axle assembly, for instance. One of the assemblies may be carried in the mid zone of the length of each axle, or, if preferred, there may be an assembly for each wheel, thus placing the mounting in the vicinity of the end of the axle.

During normal vehicle use, the jack is in its inactive nested condition, illustrated in Figures 1 and 4. In such position spaces 19 and 23 are filled with air, with ports 14, 15 and 18 closed. Since port 18 forms the only outlet from the spaces 19 and 23, it can be understood that the closed port 18 traps the air in these spaces, thus cushioning sections 12 and 13, thereby aiding the clips 26 in holding the jack in nested position.

Since, during the previous nesting cycle, the sections 13 and 12 were raised to nested position with their top marginal faces contacting the inner top face of section 11 by the filling of spaces 19 and 23 with air which was then trapped by the closure of port 18, the only portion of the top surface of the assembled sections 12 and 13 freely accessible for fluid-pressure supply through port 14 is the space 12b in the top of section 12, the contacting marginal top faces of these sections preventing any material leakage of air beyond such depressed zone 12b. Hence, when port 14 is opened for service, its pressure effect is limited to the top of section 12 without placing any material pressure on the top flange 24 of section 13. When, therefore, after hooks 26 are released, port 18 is opened in succession to port 14, the pressure on the top of section 12 causes the latter to begin downward movement, its flange 24 forcing the previously trapped content from space 23 out through ports 22 into the outer space 19; inasmuch as ports 22, like port 18, are in the lower zone of space 19, and top of section 12 is being subjected to the maximum pressure, with no material pressure being applied to the top of section 13, it will be understood that the supply of trapped air exhausted through port 18 is, in effect, being supplied from inner space 23 although actually reaching port 18 from space 19, port 18 controlling the rate of discharge and thus controlling the rate of downward travel of section 12; section 13 remains stationary during this downward travel since no material pressure is being applied to section 13 and space 23 is supplying all the pressure taken by port 18, the major portion of the content of space 19 thus remaining within the space.

This condition will continue until the flange 24 of section 12 reaches and contacts flange 21a of section 13, thereby completing the full length of the stroke of section 12, the latter being the only movable section during this period, and is made possible through the fact that ports 22 have not changed position during this period. As indicated in Fig. 2, this practically evacuates the space 23 from its trapped air content. The period constitutes the first stage of the expansion cycle.

Since the pressure supply through port 14 continues after contact of flanges 24 and 21a, section 12 becomes a power source for drawing section 13 downward, with section 12 traveling with section 13. After the downward movement of section 13 begins, its flange 20 also is exposed to the pressure through port 14 to aid in moving

section 13 downward. The beginning of such downward movement of section 13 will carry ports 22 into the zone of flanges 17 and 17a of section 11, and while traveling through this flange zone, ports 22 will be closed off; in the expanding cycle, such cut-off does not affect the operation, since inner space 23 is practically evacuated at such time. When, however, the downward travel of section 13 below such flanges exposes ports 22 below the flanges communication with the inner space 23 is reestablished but the communication is with the atmosphere and not the fluid pressure. Such communication is provided to permit the free expansion and contraction of the inner space 23 whenever needed in the further development of the cycle.

This downward travel of sections 13 and 12 together will continue until the foot 25a contacts the supporting surface, which may be the traction surface or the block 30, preventing further downward movement of the inner section 12, the pressure from port 14 however, continuing action on the closed top of the section, thus firmly holding it in position on the surface; this pressure also continues on flange 20 of section 13, and since there is no restraint on the downward movement of the latter, this section continues to travel down until flange 20 seats on flange 17a of the outer section 11; this flange contact remains constant during the remainder of the expansion cycle. This has the effect of evacuating the outer space 19 of its trapped air, and ends the second stage of this cycle—the positions of the sections at such time is shown in Figure 5.

The third and final stage of the cycle is that of raising the vehicle and is produced by the continued application of pressure from port 14, port 18 being now preferably closed, since space 19 is evacuated and space 23 is in open communication with the atmosphere through ports 22. Such admitted pressure from port 14 raises section 11, the latter drawing section 13 with it, due to the contacting flanges 17a and 20, the distance of raise being controlled by the operator who closes port 14 when the vehicle has reached the desired height; the maximum distance possible carries section 13 to the position shown in Fig. 6, but whatever the distance may be the vehicle weight is holding the expanded jack firmly to its supporting surface through the trapped pressure within section 11 and within the open top of section 13 and applied to the top of section 12, section 13 being held from rising from its seated position by the pressure on its flange 20.

The nesting cycle is likewise of three-stage type, the first stage being that of lowering the vehicle until its wheels contact the traction surface, the action being produced by opening port 15, leaving ports 14 and 18 closed. This returns the sections to the positions of Fig. 5, with inner space 23 open to the atmosphere through ports 22 and ends this first stage of the nesting cycle.

The second stage of the nesting cycle is begun by opening port 18 with its pressure-supply formation active. This admits pressure to the evacuated outer space 19 causing flange 20 to rise and thus raise section 13, this rise continuing until the marginal top of the section contacts the inner face of the top wall of section 11, thus filling space 19 with pressure air and ending the second cycle. The movement of section 13 during the cycle is relative to section 12 as long as ports 22 remain below flange 17, the content of space 23 exhausting through ports 22 during such period. However, when ports 22 pass into the zone

of the flange formation 17-17a, the ports 22 are temporarily closed by the formation, preventing further escape of content from space 23 until the ports emerge above flange 17a; while the ports are so closed, section 12 will move upward with section 13 for a distance equal to the depth of the flange formation.

The third and final stage of the nesting cycle is that of raising section 12 to its nested position, 10 and begins with the exposure of ports 22 above flange 17a, thus opening communication between the two spaces; since space 19 has been filled during the second cycle, the continued introduction of pressure into space 19 through port 18, causes 15 the excess pressure to enter space 23 and become effective to raise flange 24, thus raising section 12, the raising movement continuing until the marginal top of section 12 contacts the top wall of section 11, the fingers 26 being applied at the 20 close of the stage.

As indicated by the above, the two cycles—expansion and nesting—of the regimen controlling the jack operation in service are each composed of three stages which develop successively in each cycle. With the nested assembly having the 25 spaces 19 and 23 filled with trapped fluid pressure, the regimen begins with the first stage of the expansion cycle, during which the content of the inner space 23 is evacuated, the inner section 12 being the sole movable section with the movement that of a complete stroke of the section. The second stage is purposed mainly to evacuate the trapped fluid pressure of the outer space 19 and incidently to open the inner space 23 to the 30 atmosphere; both sections 12 and 13 travel together during a portion of the stage, after which section 13 continues alone to complete its full stroke. The third stage is the raising of the vehicle, the outer and intermediate sections 11 and 35 13 being movable together during the stage.

The nesting cycle presents as its first stage, the lowering of the vehicle—with the outer and intermediate sections movable together. The second stage is designed to restore the fluid pressure to the outer space 19 and move section 13 to its nested position; section 13 moves alone during the greater portion of its stroke, section 12 traveling with it, during the period when ports 22 are passing the flanges 17 and 17a; section 13 thus travels its complete stroke length. The third and final stage is designed to restore fluid pressure content to the inner space 23 and to position the inner section in its nested position; with the exception of the short distance it travels with section 13 during the second stage, the travel of the inner section 12 is of the length of its stroke—during the stage the section travels alone.

The stages of the two cycles are somewhat 60 similar in type but in reverse order, the initial and final stages of the regimen dealing with the inner space 23 through the movement of the inner section 12 as the sole movable section during these stages; the middle stage of each cycle pertains more particularly to the outer space 19 and the free movement of atmosphere into and out of inner space 23—section 13 travels alone and also together with section 12. The successive stages forming the final of the expansion cycle and the initial of the nesting cycle, pertain to the vehicle movement—the outer and intermediate sections travel together during these stages. There is thus a systematic order characteristic present throughout the regimen which 65 greatly simplifies the jack operation.

The three sections disclosed will permit the assemblage to be formed with an overall nested dimension such as to provide an adequate road clearance effect and at the same time assure ample expansion—especially the block 50 available—so that the assemblage is sufficiently small in axial dimension as to provide efficient service, and at the same time is so formed as to provide adequate strength and form for the purpose for which it is designed.

The jack is constructed of comparatively few parts with each having a form permitting of sturdy construction as well as ready production so that the cost of production is reasonably low although it is very efficient in service.

While I have herein shown and described a preferred form of the invention, it is apparent that changes or modifications therein may be found desirable or essential in meeting the exigencies of service or the desires of an individual user, and I therefore reserve the right to make any and all changes desirable or essential insofar as the same may fall within the spirit and scope of the invention as expressed in the accompanying claims when broadly construed.

What is claimed as new is:

1. The combination with a vehicle, of a lifting jack assemblage permanently mounted thereon, said assemblage comprising three coaxial sections relatively movable telescopically into and out of a nested relation with the outer section permanently positioned on the vehicle, said sections being in concentric spaced relation with the spacing provided by flanges carried by section end zones to form end closures for the respective spaces, opposite spacing members of a space being relatively movable by section telescoping movement to permit variations in volumetric space dimensions in the direction of the axis of the section telescoping movements, the lower zone of the intermediate section above and in the vicinity of the spacing flange being perforated to permit communication between such spaces while the intermediate section is in nested position, the assemblage having the outer section as open-bottomed, the intermediate section as open-ended both top and bottom and the inner section having a closed top and bottom, and controllable independent fluid pressure supply and exhaust means carried by the outer section, said means including a supply and an exhaust carried by the top in a mid-zone of the outer section and a fixture serviceable both for exhaust and supply positioned in the lower zone of a side wall of such outer section, said assemblage having the top face of its inner section formed to annularly contact-engage the inner top face of the outer section beyond such mid-zone of the latter when the sections are in nested relation, the inner section top face having a depressed mid-zone accessible to the fluid pressure supply in such nested relation, to thereby restrict initial fluid pressure activity solely to the closed top zone of the inner section, said assemblage having a service regimen consisting of a stage expanding cycle and a stage nesting cycle with the sections in nested relation during service inactivity, said assemblage regimen being characterized in that the initial stage of the expanding cycle presents the inner section as the sole moving section of the assemblage with the movement extending throughout the individual stroke length of the section, the movement of said inner section in its nesting direction constituting the sole moving section during the final stage of the nesting cycle of the regimen with 60

the movement extending substantially throughout the individual stroke length of the section.

2. An assemblage as in claim 1 characterized in that the position of the perforate zone of the intermediate section is such as to permit approximately complete evacuation of the volumetric content of the inner space into the outer space during and by such initial stage movement of the inner section and en route to the assemblage 10 exhaust and to concurrently maintain the intermediate section in its nested position during such stage.

3. An assemblage as in claim 2 characterized in that the relative position of the spacing flanges 15 on the inner and intermediate sections respectively is such that the close of the individual stroke length of the inner section at the end of the initial stage places said flanges in contact engagement to thereby constitute said inner section 20 as a power source for drawing the intermediate section from its nested position and to thereby render the upper spacing flange of such intermediate section subject to the assemblage fluid pressure to render both sections active to discharge content of the outer space and thereby produce the second stage of the expansion cycle and to place the lower end zone of the inner section 25 in its position for supporting the expected load with the latter constituting the third stage of the expansion cycle, the load being produced by the upward movement of the outer section relative to the inner section with the intermediate section idly rising with the outer section.

4. An assemblage as in claim 3 characterized in that the position of the spacing flanges carried by the outer section relative to the position of the perforate zone of the intermediate section in nested position is such that while the intermediate section is in nested position the spacing flanges of the outer section form the lower bounds of the outer space with the perforate zone located above such outer section flange, the expanding movement of the intermediate section being operative to carry its perforate zone below 40 the outer section flange and to open communication with the atmosphere therebelow to thereby render the inner space freely variable as to volumetric dimensions produced by movements of the inner and intermediate sections relative to each other in opposite directions while such perforate zone is so exposed.

5. An assemblage as in claim 1 characterized in that the stage development of the nesting cycle is substantially the reverse in order to that of the expansion cycle, the direction of advance of the inner and intermediate sections in one cycle being reversed when the action is in the other cycle.
